W. EGGERS.
MOLD FOR MAKING RUBBER ARTICLES.
APPLICATION FILED JUNE 25, 1914.

Reissued Sept. 28, 1915.

13,988.

UNITED STATES PATENT OFFICE.

WILLIAM EGGERS, OF NEW YORK, N. Y.

MOLD FOR MAKING RUBBER ARTICLES.

13,988.

Specification of Reissued Letters Patent. Reissued Sept. 28, 1915.

Original No. 1,049,688, dated January 7, 1913, Serial No. 586,968. Application for reissue filed June 25, 1914. Serial No. 847,564.

To all whom it may concern:

Be it known that I, WILLIAM EGGERS, a citizen of the United States of America, residing in the city of New York, borough of Brooklyn, in the county of Kings and State of New York, have invented certain new and useful Improvements in Molds for Making Rubber Articles, of which the following is a specification.

10 This invention relates to an improved mold for making rubber articles, and more especially hollow rubber articles, such as bulbs, nipples and the like.

Heretofore, the rubber articles were 15 molded in a solid cast-metal mold, which was provided with a number of cavities, into which the soft rubber was placed in unvulcanized condition and vulcanized in the mold. These molds were made of a solid 20 casting and were heavy and inconvenient in handling.

The object of this invention is to overcome the objection to the molds heretofore used for making hollow rubber articles, 25 furnishing a mold of comparative lightness, which can be easily handled and in which detachable shells, corresponding to the shape of the rubber articles to be made, are employed and placed into suitable supporting-frames having openings for receiving 30 the shells; and for this purpose the invention consists of a mold for making hollow rubber articles, which comprises a supporting-frame provided with openings, a plurality of soft metal shells inserted into said 35 openings, said shells being made of cast-metal and swaged into shape.

The invention consists further in making the shells of cast soft metal swaged into 40 shape.

In the accompanying drawings, Figure 1 represents a perspective view of my improved mold for making hollow rubber articles, Fig. 2 is a perspective view of the 45 lower section of the mold, Figs. 3 and 4 are vertical transverse sections on line 3—3, Fig. 1, and 4—4, Fig. 2, drawn on a larger scale, and Fig. 5 is a vertical transverse section through one of the shells used in my improved mold.

Similar letters of reference indicate corresponding parts throughout the several figures.

In making my improved mold for rubber articles, a number of shells *a* are cast of suit-

able soft metal, such as tin, type-metal, aluminum or the like, in molds having a number of cavities corresponding to the shells to be produced. After the material of the shells is cooled off, they are removed from the mold and are then placed into a die of corresponding shape, into which a steel plunger is pressed, so that the soft metal shell is swaged into final shape. After the swaging process, the shell is taken out from the die, being then complete and free from all defects and highly polished, owing to the pressure exerted on the shell during the swaging process. These shells form the essential part of my improved mold. A plurality of shells *a* are inserted into a frame *f*, which forms the lower section of the mold and which is provided with as many openings as shells *a* are to be used. The shells of the lower section are seated by their circumferential rims *a'* into corresponding recesses *o'* of the supporting-frame *f*, around the openings *o*. The shells are preferably spaced at this lower part from the walls of the openings, as shown. A second supporting-frame *f'*, forming the upper section of the mold, is provided with the same number of shells which fit on the shells of the lower supporting-frame, as shown in Fig. 2. The upper section is then placed over the shells 85 of the upper and lower frames and locked thereto by means of clamping-screws *e*, which are pivoted to the lower sections and are made to engage recessed ears *e'* at opposite ends of the upper section, so as to 90 lock the molds rigidly together.

Before locking the lower and upper sections of the mold together, the layers of soft unvulcanized rubber are placed on the interior of the shells, both in the female shells 95 of the lower as well as the male shells of the upper frame, the shells of the upper section being placed over the shells of the lower frame, after which the upper frame is placed in position over the upper shells and locked 100 to the lower frame as before described. The mold is then transferred to the vulcanizing-oven. After vulcanization the mold can be quickly cooled off, by being submerged in water, and is then taken apart so that the vulcanized articles can be readily removed from the molds.

The advantages of my improved mold are first, that the shells can be removed and replaced at will, and that they are so con- 110

structed that they will always be centered by the fitting of the male shells of the upper mold-section with the female shells of the lower section. Second, that the molds can be kept always in perfect condition by replacing any defective shells by new shells; third, that the molds can be made and used either as single, individual molds, or combined as so-called "gang-molds," so that considerable time is saved in the use of the same. The main point of advantage, however, consists in the facility with which the improved molds can be handled, owing to their comparative light weight as compared with the heavy, clumsy molds heretofore used.

By substituting my improved molds for the heavy cast-metal molds heretofore in use, the vulcanizing work to be done in factories making hollow rubber articles, is greatly facilitated and cheapened, inasmuch as the cost of making and maintaining the molds is reduced to a great extent, while the articles

manufactured by the improved molds are superior to those made in the old-style molds. 25

Having thus described my invention, I claim as new and desire to secure by Letters Patent:

1. A mold for making and vulcanizing rubber articles made of soft metal having 30 the interior thereof solid and swaged to a highly polished surface.

2. A mold for making and vulcanizing rubber articles, comprising a cast solid soft metal member of shell form, having its interior swaged to a highly polished surface, and having its shell-like walls of substantially equal thickness. 35

In testimony, that I claim the foregoing as my invention, I have signed my name in 40 presence of two subscribing witnesses.

WILLIAM EGGERS.

Witnesses:

C. P. GOEPEL,
JOSEPH BISBANO.
